(57) **CLAIM**

The ornamental design for a dissolvable release acidizing plug as shown and described.

DESCRIPTION

FIG. 1 is a front elevational view of a dissolvable release acidizing plug showing our new design;

FIG. 2 is a left side elevational view thereof;

FIG. 3 is a top elevational view thereof; and,

FIG. 4 is a bottom plan view of the design shown in FIG. 2. The broken lines in the drawings depict portions of the dissolvable release acidizing plug that form no part of the claimed design.
